UNITED STATES PATENT OFFICE.

FERDINAND JOHN BOEHL, OF SPOKANE, WASHINGTON.

WINDOW-SCREEN.

No. 872,891.

Specification of Letters Patent.

Patented Dec. 3, 1907.

Application filed April 24, 1907. Serial No. 370,085.

To all whom it may concern:

Be it known that I, FERDINAND JOHN BOEHL, a citizen of the United States, and resident of Spokane, in the county of Spokane and State of Washington, have invented an Improvement in Window-Screens, of which the following is a specification.

My invention is an improvement in the class of window-screens which are formed of woven wire or wire gauze attached to wooden frames, the construction and arrangement being such that side openings are provided through which flies and other insects may freely escape from a room or apartment, but are prevented from returning.

The invention is embodied in the construction, arrangement, and combination of parts hereinafter described, and illustrated 20 in the accompanying drawing, in which

Figure 1 is a face view of a window-screen constructed according to my invention, a portion of the screen proper being cut away for sake of better illustration. Fig. 2 is a 25 side edge view of the screen. Fig. 3 is a transverse section on the line 3—3 of Fig. 1. Fig. 4 is an enlarged transverse section similar to Fig. 3.

The rectangular wooden frame to which 30 the screen proper is applied, comprises parallel side bars 1 and parallel top and bottom bars 2 and 2^a. The bars 1 and 2 are beveled on the outer side, as indicated in Figs. 3, 4, and to such beveled portion is 35 attached a narrow piece or strip 3 of woven-wire, or wire-gauze, the outer edge of the same projecting outward beyond the bevel but not beyond the side of the frame. A piece 4 of wire-gauze having the same form as the 40 frame, is applied to the latter so that its side and top edges extend as far laterally as the narrow strip 3, the supports and spacing devices 5 being arranged between them and secured by nails to the frame. Such devices 45 are beveled on the inner side, while their outer sides are in a plane parallel to the face, or flat side, of the frame. They are made preferably of sheet metal cut and bent to the proper form and provided with holes for 50 receiving the securing nails or screws. The same nails or screws that secure the devices 5 pass also through the narrow strips 3, and thus aid in securing the latter flat upon the bevel of the frame. As indicated in Figs. 2, 55 3, and 4, the strips 3 and screen 4 are separated at their outer edges by a space wide

enough for the passage of flies and various other insects, the inner ends of the spaces being, however, much wider, so that the insects will be induced to crawl along either 60 of the screen parts 3 or 4, and thus led or guided toward the exit. At the same time, the outer edges of the parts 3, 4, are sufficiently near each other and present such rough or ragged edges, that the entrance of 65 insects is effectually prevented. The lower end of the screen 4 is secured by nails to the lower cross bar 2^a of the frame, and extends a short distance below the same as indicated in Figs. 1 and 2. The said bar projects from 70 the face of the side bars 1, far enough to hold the lower portion of the screen 4 duly separated from the adjacent portions of the side strips 3.

The bevel formed at the outer sides of the 75 bars 1, 2, does not materially weaken the frame, and at the same time provides for attachment and firm support of the wire strips 3, while the free side edges of the latter project beyond the bevel so as to permit 80 the passage of light through them, which is important in inducing the flies or other insects to pass out through the lateral openings. The side bars 1 also extend below the bottom bar 2^a the same distance as the 85 screen 4. The object of this constructive feature is to allow rain water, or water discharged upon the screen from a hose in washing the windows, to pass down and find free escape under the bottom bar 2^a, it being understood that the ends of the side bars 1 in 90 practice rest upon the ledge, or sill, of a window.

It will be understood that my invention is applicable to screens for doors as well as 95 windows.

I claim:

1. The combination with a frame having its inner outside edges beveled, and narrow woven-wire strips secured thereto and their 100 outer edges projecting beyond the bevel, of a woven-wire sheet applied to the frame, and devices interposed between its edges and the aforesaid strips, the outer sides of said devices being in a plane parallel to the frame, 105 whereby lateral escape openings are formed between the edges of the said strips and sheet, said openings being widest at their inner ends, as and for the purpose set forth.

2. The improved screen comprising a rectangular frame having side bars extended below the bottom bar, and a screen secured 110

to the face of the frame and its lower edge extended below the bottom bar, as and for the purpose specified.

3. The improved screen comprising a rectangular frame having woven-wire strips applied to the side bars, and a woven-wire sheet extending over the whole frame and below the bottom bar thereof, means being

provided at the lower corners of the frame for supporting the bottom bar out of contact 10 with a ledge, or other part, upon which the screen may rest, substantially as described.

FERDINAND JOHN BOEHL.
